UNITED STATES PATENT OFFICE.

JOHN K. STEWART, OF CHICAGO, ILLINOIS, ASSIGNEE TO STEWART-WARNER SPEEDOMETER CORPORATION, OF VIRGINIA.

ODOMETER-TRAIN.

1,110,835.

Specification of Letters Patent. Patented Sept. 15, 1914.

Application filed August 26, 1912. Serial No. 717,901.

To all whom it may concern:

Be it known that I, JOHN K. STEWART, a citizen of the United States, residing at Chicago, in the county of Cook and State of Illinois, have invented new and useful Improvements in Odometer-Trains, of which the following is a specification, reference being had to the accompanying drawings, forming a part thereof.

10 The purpose of this invention is to provide an improved construction for odometer trains designed particularly with a view to durability and freedom from necessity of repair.

15 It consists of the various elements and their combinations described and shown in the drawings as indicated in the claims.

In the drawings:—Fig. 1 is a face view of an instrument embodying the odometer train which is the subject of this invention. Fig. 2 is a plan view of the train. Fig. 3 is a somewhat diagrammatic view of certain parts cut by the plan at line 3—3 on Fig. 2. Fig. 4 is a similar diagram taken at line 25 4—4 on Fig. 2. Fig. 5 is also a diagram taken at line 5—5 on Fig. 2. Fig. 6 is a medial section of the trip-recording train being section lined in a manner to indicate the obvious possibility of forming the gears 30 of the dial wheels integrally with said wheels. Fig. 7 is a diagrammatic section taken at line 7—7 on Fig. 2. Fig. 8 is a detail elevation of an end-bearing of the train.

The odometer train which is the subject of 35 this invention is designed with a view to eliminating in so far as possible the use of springs or pawls in the distance recording mechanism, and is therefore positively gear-driven throughout. As shown in the drawings, it is duplex in arrangement, providing for the registration of total travel and also for separately registering comparatively short distances by means of a train which may be reset to the zero point at any time.

45 The total mileage register consists of a set of dial wheels or cylinders, A, mounted upon an arbor, A¹, while the trip-registering dials, B, are similarly mounted along the same axis but in a separate group, so as to 50 appear at a separate window in the case of the instrument as indicated in Fig. 1. Both trains are driven by any suitable connections through the worm shaft, C, having a worm, C¹, meshing with a gear, D, which is 55 rigidly connected through a common shaft

with a spur gear, E. The gear, E, meshes with a pinion, F, which in turn drives a gear, G, mounted for rotation about the axis of the dial wheels, A and B.

As shown, the trip odometer consists of 60 but three dials, the right hand dial being intended to indicate tenths of miles, while such minute accuracy is not considered necessary in the total distance register, and the last or right hand dial, A, is geared to register 65 single miles. The tenths mile dial, B¹, is therefore connected directly to the gear, G, through a shaft, H, while the right hand or initial dial, A, of the total registering train is intermittently driven by a mechanism 70 which will now be described.

With a single exception, each of the numeral dials or cylinders is provided at one side with a continuous spur gear, A², of 75 twenty teeth, and at the other side with a mutilated gear, A³, of two teeth only, together with a notched plate, A⁴. This two-toothed gear, A³, stands adjacent to the twenty-toothed gear of the next cylinder, and connection between the two is made in 80 each case by an idler pinion, J, loosely mounted on a side shaft, K, and constructed with alternating full-width and short-width teeth, J¹ and J², respectively. The full-width teeth by overhanging the periphery 85 of the plate, A⁴, as shown in Fig. 3, lock the pinion, J, as well as the intermeshing gear, A², of the adjacent dial cylinder and prevent their rotation, except during the passage of the two teeth of the gear, A³, 90 when the notch, A⁴⁰, of the plate, A⁴, meshes with a full-width tooth of the idler, J, said plate, A⁴, being so mounted that its notch, A⁴⁰, registers with the space between the two teeth of the gear, A³. Each complete revolution of the mutilated gear, A³, 95 with its numeral dial causes a movement of the adjacent dial by an amount measured by two of the twenty teeth of its gear, A², that is, one tenth of a revolution. The same 100 principle is employed for driving the right hand or initial dial of the train by providing on the shaft of the worm gear, D, a mutilated gear of two teeth, D¹, and a notched plate, D², which are identical in 105 form with the gears and plates associated with the numeral dials, and are thus adapted to mesh with the idler pinion, J, which meshes with the twenty-toothed gear, A², of the said initial dial cylinder. Thus for 110

each revolution of the worm gear, D, the said initial dial is moved one-tenth of a revolution, while since the gears, E and G, are of equal size, the initial or tenth mile dial of the trip odometer is moved through a complete revolution. It will be understood that the remaining dials, B, of the trip odometer are connected with the initial dial in a manner similar to that employed in the 10 total mileage register, as above described.

It will be seen that particularly in the total mileage register where there are five dials, each dependent on the preceding one for its movement, such movement being communicated to it through one of the idler pinions, J, that any slight back-lash between the pinions, J, and the gears, A², would be cumulative in its effect upon the final dial of the train, so that this final dial 15 would appear to be quite loosely coupled with the initial dial of the train, and its numerals might fall very noticeably out of alignment with the numerals of said initial dial in appearing at the window of the casing. The same thing would be true to a lesser extent of the intermediate dials of the train, and the result would be a poorly aligned row of figures at the window. To obviate this possibility there is provided a 20 flat spring arm, L, having its free end resting against the idler, J, which meshes with the final one of the dial gears, A². The end of this arm is slightly up-turned at, L¹, as shown in Fig. 7, to transmit a pressure directly against one of the full-width teeth, J¹, of the idler for forcing it into contact with the circumference of the notched plate, A⁴, thus transferring the back-lash space from this point of contact to the point, J^x, 25 as indicated in Fig. 7. By virtue of the relative directions of rotation of the dial gears and the pinions, J, any back-lash or lost motion will tend to appear as a space between the tooth, J¹, and the surface of the plate, A⁴, at the upper side of their axes, and the action of the spring, L, is thus to 30 complete the movement of the idler, J, which was left unfinished by reason of the lost motion, while said idler, J, in turn acts upon the gear, A², of the final dial to bring it to the normal position of rest so that the figure of the numeral dial will be properly positioned with respect to the window in the casing. Obviously the same expedient 35 might be applied to each and every one of the idlers, J, but it is found sufficiently effective for practical purposes to employ it only as illustrated.

To permit the resetting of the trip-registering train, this train beginning with the gear, G, and including the pinions, J, which are engaged between the consecutive dial wheels, B, so as to be carried laterally therewith along the shaft, K, of the pinions, is 40 made slidable bodily along the axes of the

dial wheels and pinions for simultaneously withdrawing the gear, G, from engagement with its driving pinion, F, and for bringing a pinion, B^x, into mesh with the resetting gear wheel, M. The shaft of the gear, M, 45 is extended outside the case of the instrument where it is provided with a knurled hand wheel, N, and since the gear, M, is several times larger than the pinion, B^x, which is rigid with the initial dial of the 50 trip train, it will be seen that the train may be rapidly reset by the rotation of the wheel, N, rotating all the dial wheels in the same manner as they would be rotated in service in either direction until they stand at any 55 desired position, —i. e., either all at zero or at any other point at which it is desired to commence, or from which it is desired to continue, the count of the trip mileage. The sliding movement of the train upon its axis 60 is accomplished by means of a shifter lever, P, which engages a groove, H¹, near the end of the shaft, H, and is arranged to be operated by a push button, Q, extending outside of the case of the instrument, while a 65 spring, T, is connected for yieldingly maintaining the normal position of the train, that is, with the gear, G, in mesh with its pinion, F.

For convenience of assembling, the spindle or arbor, A¹, which carries the total mileage dials is merely slipped into its bearings at, A⁶ and A⁷, being retained in position by a hook-shaped catch, A⁸, which engages a groove, A⁶⁰, in the protruding end 70 of the arbor, while its opposite end retains in position the bent end of the side shaft, K, as indicated at, K¹, in Fig. 8. This hook, A⁸, is secured to the bearing, A⁶, by a screw, A⁹, by which it may be firmly clamped in 75 position to insure that the parts, K and A⁶, will be permanently retained in place.

I claim:—

1. In a revolution counter comprising a plurality of dial wheels and means whereby 80 they are serially geared together, driving means normally engaging the initial wheel of such series for actuating the train, auxiliary driving means adapted for manual operation and standing normally disengaged 85 from the train, and means for disengaging the regular driving means from said initial wheel without affecting the serial connection of the dials, and simultaneously connecting said auxiliary means therewith to 90 permit manual setting of the dials to any desired reading.

2. In a revolution counter comprising a 95 casing, a plurality of dial wheels and means whereby 100 they are serially geared together, driving means normally engaging the initial wheel of such series for actuating the train, auxiliary driving means extending outside 105 said casing and adapted for manual operation and standing normally disengaged from 110

the train, and shifting means also extending outside the casing arranged for disengaging the regular driving means from said initial wheel without affecting the serial connection of the dials, and simultaneously connecting said auxiliary means therewith to permit manual setting of the dials to any desired reading.

3. In a revolution counter comprising a series of dial wheels rotatably mounted upon a common shaft, gears associated with said dial wheels, respectively, idler pinions rotatably and slidably mounted on a parallel shaft in mesh with said gears for serially connecting the dial wheels to one another, and driving means engaging the initial wheel of the train, means for shifting said dial wheels with their idlers longitudinally of their respective axes of rotation for disengagement from said driving means and manually operable driving means, adapted for connection with the initial wheel of the train at such shifted position for re-setting the dials to any desired reading at will.

4. In an odometer train comprising a plurality of dial wheels co-axially mounted, and a series of idler gears positioned for operatively connecting adjacent dial wheels of the train; an arbor for said dial wheels; a shaft for the idlers, one end of said shaft being bent; bearing lugs apertured to receive said arbor and shaft, one of said bearings having a notch extending transversely from its shaft-receiving aperture to accommodate the bent end of said shaft, the arbor being formed near its end with a circumferential groove, and a hook-shaped locking plate secured to the said bearing lug with its hook engaging the groove of the arbor and with its opposite end covering the notch which lodges the bent end of the shaft.

In testimony whereof, I have hereunto set my hand at Chicago, Illinois, this 22nd day of August, 1912.
